CLAIM

The ornamental design for a prescription lens holder for safety spectacles, as shown and described.

DESCRIPTION

FIG. 1 is a front elevational view of a prescription lens holder for goggles showing my new design, the rear elevational view being a mirror image;
FIG. 2 is a right side elevational view thereof, the side opposite being a mirror image; and,
FIG. 3 is a top plan view thereof.

FIG. 1

FIG. 2

FIG. 3
